United States Patent Office

Des. 175,736
Patented Oct. 4, 1955

175,736

CHENILLE FABRIC OR SIMILAR ARTICLE

Edwin Morgan and Theodore C. Sippel, Laurinburg, N. C., assignors to Scotland Mills, Incorporated, Laurinburg, N. C., a corporation of North Carolina

Application July 26, 1954, Serial No. 31,607

Term of patent 14 years

(Cl. D92—1)

FIG. 1.

FIG. 2.

We claim:

The ornamental design for a chenille fabric or similar article, as shown.
